TOY SHOOTING TARGET OR SIMILAR ARTICLE

Laurie Jay Campbell, Erie, Pa., assignor to Louis Marx
& Company, Inc., New York, N.Y., a corporation of
New York

Filed Dec. 7, 1967, Ser. No. 9,678

Term of patent 14 years

Int. Cl. D21—02

U.S. Cl. D34—5

FIG. 1 is a front elevational view of a toy shooting target embodying my new design;

FIG. 2 is a top plan view thereof;

FIG. 3 is an end view thereof;

FIG. 4 is a view similar to FIG. 3 showing the opposite end of the assembly; and

FIG. 5 is a bottom plan view thereof.

I claim:

The ornamental design for a toy shooting target or similar article, as shown.
